UNITED STATES PATENT OFFICE.

AUGUSTUS L. MEROLLE, OF BROOKLYN, NEW YORK, ASSIGNOR TO EMPIRE METAL CAP CO. INC., OF BROOKLYN, NEW YORK, A CORPORATION OF NEW YORK.

RECEPTACLE CLOSURE.

Application filed December 30, 1922. Serial No. 609,991.

To all whom it may concern:

Be it known that I, AUGUSTUS L. MEROLLE, a citizen of the United States, residing at Brooklyn, in the county of Kings and State of New York, have invented certain new and useful Improvements in Receptacle Closures, of which the following is a specification.

This invention relates to a receptacle closure, and an object of the invention is to provide a closure of the simple screw type and in which means is provided affording a highly efficient finger grip for use in attaching and detaching the closure.

15 A further object is to provide a closure of this type having a wire-edge formed thereon by turning up the material at the bottom of the flange, and having specially prepared parts disposed adjacent to the wire-edge so as to reinforce the same against distortion and so as to cooperate therewith in providing an efficient finger grip.

20 A further object is to so form the material of the flange of the closure adjacent to the threads thereof as to provide a desirable flexibility in said flange and threads so as to enable the threads to more readily accommodate themselves to the threads of the receptacle.

25 Other objects and aims of the invention, more or less specific than those referred to above, will be in part obvious and in part pointed out in the course of the following description of the elements, combinations, arrangements of parts and applications of principles, constituting the invention, and the scope of protection contemplated will be indicated in the appended claim.

30 In the accompanying drawings which are to be taken as a part of this specification, and in which I have shown merely a preferred form of embodiment of the invention:—

Figure 1 is a side elevational view of a 35 closure constructed in accordance with this invention, the same being illustrated as applied on to a receptacle.

Figure 2 is an enlarged detail sectional view thru a portion of the closure seen in 40 Fig. 1.

Referring to the drawings for describing in detail the structure therein illustrated the reference character L indicates the receptacle which is of course open at its upper 45 end and which is preferably provided with

an annular outstanding bead 1 thereon spaced downwardly from the upper end of the receptacle. Between the bead and the upper end is provided suitable outstanding threads 2 with which the closure is intended 60 to engage by interrotation of said parts in the usual manner.

The reference character G indicates generally the closure device, the same being made up of a cover part 3 and an annular 65 marginal flange 4 provided thereon for depending about the exterior of the receptacle. The entire closure is formed from a single piece of sheet metal pressed or drawn into shape, and the flange portion 4 thereof is 70 pressed to provide the threads 5.

It is to be particularly noted that the threads 5 do not extend for the full width of the flange but that on the contrary they are confined to the central portion of the 75 flange, i. e. to the region defined by the lines 6 and 7 in Fig. 2. The portion of the flange above the region of the threads, i. e. between the line 6 and the top of the closure as defined by the line 8, is formed with 80 vertically extending corrugations 9. While the portion of the flange below the threads, i. e. between the lines 7 and 10 is formed with a second series of vertical corrugations 85 as 11. Below the corrugations 11 is formed the wire-edge 12 which, as will be seen in the drawing is formed by bending up the material of the flange. The lower portions of the corrugations 11 stand substantially in contact with the upper portion of the 90 wire-edge and thus efficiently reinforce the wire-edge at all times.

The corrugations 11, projecting outwardly above the wire-edge also serve to protect said wire-edge against injury, and here it 95 is to be noted, as shown by the line 13 in Fig. 2, that the corrugations 11 preferably extend outwardly to substantially the same vertical plane as the outermost portion of the wire-edge so that in this way said corrugations 11 not only form a very efficient protection for the wire-edge but also are given sufficient prominence so that they constitute an efficient finger grip.

It is also to be noted that by corrugating 105 and distorting the material of the flange adjacent to the lower portion of the threads there is provided a certain appreciable degree of flexibility and elasticity in said threads, and particularly in the lower por- 110

tions of said threads, which will enable the threads to accomodate themselves readily to the contour of the threads 2 of the receptacle.

The corrugations 9 arranged immediately above the threads also provide a certain degree of elasticity and flexibility in the threads and particularly in the upper portions of the threads, thus augmenting the effects of elasticity and flexibility afforded by the lower corrugations. The threads may be correctly defined therefore as floating between the upper and lower portions of the flange.

It is also desired to note that whereas the corrugations 11 are formed substantially wholly by being pressed outwardly beyond the normal plane of the flange, said plane being indicated by the double dotted line 14 in Fig. 2, the corrugations 9 are formed by pressing the material of the flange partly outward of said plane and partly inward of said plane. By this means the corrugations 11 are made to project outwardly to a greater extent than the corrugations 9 and a corresponding and graceful upwardly tapering appearance is given to the closure. Also by setting the corrugations 9 inwardly a certain crowding of the material is felt which materially increases the elasticity and flexibility of the flange in and near the threads.

Any suitable gasket as 15 may be provided

within the closure if desired for improving the sealing, as will be understood.

As many changes could be made in this construction without departing from the scope of the invention as defined in the following claim, it is intended that all matter contained in the above description or shown in the accompanying drawings, shall be interpreted as illustrative and not in a limiting sense.

Having thus described my invention, what I claim as new, and desire to secure by Letters Patent is:—

A receptacle closure comprising cover and flange portions, the material of the flange being bent to provide threads therein spaced an appreciable distance downwardly from the upper edge of the flange, the material of the flange being also bent to provide an outstanding wire edge spaced an appreciable distance below said threads, and the material of the flange being also bent to provide corrugations extending vertically thereof in the spaces both above and below said threads, all for the purpose set forth.

In testimony whereof, I affix my signature in the presence of two witnesses.

AUGUSTUS L. MEROLLE.
